UNITED STATES PATENT OFFICE.

PATRICK H. LARKIN, OF PORTSMOUTH, VIRGINIA, ASSIGNOR OF ONE-THIRD TO EDWARD ANDERSON, OF WASHINGTON, DISTRICT OF COLUMBIA, AND ONE-THIRD TO ROBERT T. THORP, OF NORFOLK, VIRGINIA.

BOX.

No. 821,298.

Specification of Letters Patent.

Patented May 22, 1906.

Application filed May 20, 1904. Serial No. 208,974.

To all whom it may concern:

Be it known that I, PATRICK HENRY LARKIN, a citizen of the United States, and a resident of Portsmouth, in the county of Norfolk and State of Virginia, have made a certain new and useful Invention in Boxes; and I declare the following to be a full, clear, and exact description of the same, such as will enable others skilled in the art to which it app pertains to make and use the invention, reference being had to the accompanying drawings, and to letters of reference marked thereon, which form a part of this specification.

Figure 1 is a perspective view of the box with the larger section of the cover raised. Fig. 2 is a sectional view of a modified form of the box, showing a deep groove between the sections of the cover. Fig. 3 is a sectional view showing the lap-joint between the sections of the cover.

This invention has relation to cigar and cheroot boxes, having for its object the provision of such a box so constructed that the cover thereof may be partially torn off for proper access to the contents without detachment of the revenue-stamp, which is designed to be canceled in the usual manner, the entire stamp remaining in position on the top of the box for the ready inspection of the revenue officer.

With this object in view the invention consists in the novel construction and combinations of parts, as hereinafter set forth.

Referring to the accompanying drawings, the letter *a* designates the box, and *b* the cover thereof. This cover is made in two transverse parts or sections *b b²*, nearly separated by a narrow deep groove *z*, forming a weak bridge joint or connection in the bottom of the lid immediately under the inner edge of the revenue-stamp. When the dealer opens the box and breaks the stamp, if he so elects the cover-sections can be easily separated with a knife or other sharp instrument along the line of the inner edge of

the revenue-stamp and the larger portion of the lid torn off and placed under the box, the stamp remaining on the smaller section of the cover, which is not disturbed at all, and is so small as not to be in the way of ready access to all parts of the interior of the box for the removal of cigars.

Fig. 1 of the drawings shows a modification of the invention wherein the cover is made in two transverse parts or sections *b b²*, meeting in a lap-joint at one side of the box. The revenue-stamp is applied in the usual manner with the edge running over the lap-joint of the two sections of the box, sealing the joint against the entrance of air or water. When the box is opened and the stamp broken, the covers are easily separated along the line of the joint *c*, thus tearing the revenue-stamp along its edge at this point, leaving the major portion of the stamp with all necessary or distinctive markings or letterings remaining in position on the top of the smaller portion of the cover for the ready inspection of the revenue officer, while the major portion is removed and placed under the box until it is emptied and the stamp destroyed.

Having thus described my invention, what I claim as new, and desire to secure by Letters Patent, is—

1. In a cigar-box, the hinged cover composed of two transverse separable sections of unequal size, connected by a weak bridge-joint, substantially as specified.

2. A box having a lid hinged at one edge and composed of sections having their adjoining edges extending at approximately a right angle to the hinge, and a breakable connection uniting said sections along the joint.

In testimony whereof I affix my signature in presence of two witnesses.

P. H. LARKIN.
